Isaac Schmaitsmann 9422X

Patent

The Schedule referred to in these Letters Patent and making part of the same, containing a description in the words of the said Isaac Schmaitsmann himself, of his improvement in Glasses for spectacles and other optical purposes.

As all the rights these presents shall confer.

It is known that Isaac Schmaitsmann of the Ninth and Lower Liberties - County of Philadelphia and State of Pennsylvania, have invented a new and useful improvement in spectacles and that the following is a description thereof, - The improvement consists in each glass being ground with two different and distinct foci, the upper part segmental ground to a focus for discerning objects at a distance, and the lower part ground to a focus for seeing objects at hand. - In the accompanying drawings, right is intended to represent the glass as set into the rim agreeable to the pattern herewith transmitted, - being of a shape, and of a ground to these glasses as to the segments, - whether round, oval, or any other figure, suitably to the use or wishes of individuals. - The glasses are firmly set into the rims of spectacles, and the rims are made of horn, tortoise shell, gold, silver, or other metals or materials, and kept secure in the head of individuals, in the same manner as applied to spectacles, and persons seeing, these spectacles is enabled to change the focus of distance either to near or far objects and with perfect ease and convenience according as the upper or lower part of the glass is brought into operation successively before the eyes of the observer, and whenever circumstances require the change of vision which must frequently happen. In these glasses the focus is brought where it properly should be, in the centre of each particular part,

or segment - which causes them to be agreeable and pleasant to the eye. The glasses are all thickly ground, but may be ground cylindrical, but the former mode of grinding is considered preferable as being more conforming with the formation of the eye itself, whilst the cylindrical lens is still considered in some measure injurious. The glasses consist in one hand constructed for far and near sight in the same pair of spectacles are objectionable in several particulars. These glasses consist of two separate and distinct pieces or segments, each piece of different thickness and placed into each other. This making from different pieces of glass to every pair of spectacles, and when the pieces or segments meet on your the two faces come into contact by reason of this only difference in the thickness of the two pieces this causes when to be in place to the eye of not all conjuring. And as spectacles have been frequently broken or sprung from the hands in flight to offend particularly to when the river and of flight continue to be on the ground of action, and the hands have not of them trouble more and less convenient. In the case of my own power of glass, this is all that can be done, and when the hands are not near the glass it is a case of spectacles. That is done as my own experiment and not privately known, is the discovery and invention of grinding two separate and different pieces in one piece of glass, and adapt to various optical purposes best, particularly to be used and applied as spectacles of glass as is visible from figures 1, 2, 3. in the accompanying drawings herein set. In grinding these glasses each piece is being cut, whereat there is cut into the case of each separate segment. The shape of each piece of glass are cut well known among any other shapes or just as may suit the uses or wishes of individuals, who are to use them concave, convex, rounded or to split them fair and equally ground, as circumstances may render necessary, or as may be used may happen. or for magnifying may be ground, plain, or
